GREASE PUMPING MECHANISM

George H. Hartman, Bryan, Ohio, assignor to The
Aro Equipment Corporation, Bryan, Ohio, a
corporation of Ohio

Application December 15, 1930
Serial No. 502,461

4 Claims. (Cl. 103—50)

This invention relates to grease pumping mechanism and in particular to such mechanism operable by fluid pressure. My invention preferably takes the form of a pump actuated on both the intake and the delivery strokes by fluid pressure. In a grease pump of this nature now in general operation, it is customary to provide a spring to work the pump piston on the intake stroke. As the springs are generally located in an inaccessible manner, and as they are liable to breakage, I have provided means for fluid pressure operation on the intake stroke as well as the delivery stroke.

As the grease comes to the user in large drums up to a 400 lb. size I have arranged my pump for mounting external of the container, as for instance on a wall bracket. Then I have provided a suction tube to extend from the container to the pump. This forms one of the objects of my invention. As the suction tube is only a light piece of tubing or pipe, the heavy pump mechanism need not be lifted in and out of the grease container, but rather the grease container is moved to and from under the pump.

Another object of my invention is to provide means whereby the pump will charge a grease delivery line with grease under pressure and will maintain this pressure during pump delivery operations, the pump being automatically reversed to a suction stroke at the completion of each delivery stroke. This automatic operation will eliminate the attention of the operator and enable the delivery of substantially the entire contents of the grease container to the point of use.

Another object of the invention is to provide suction means that will strain out foreign matter from the grease.

Another object of the invention is to provide suction means that will distribute the effective suction area over a large portion of the bottom of the container.

Further objects and advantages of my invention are apparent for the following detailed description.

While the invention in its broader aspect is capable of embodiment in various forms, a preferred embodiment thereof, and of the mechanism forming the same, are illustrated in the accompanying drawings in which

Figure 1 is a side elevation of a grease container with the mechanism of my invention mounted thereon.

Figure 2 is a front elevation of the same with portions broken away.

Figure 3 is a perspective view of the lower end of the tube shown at the bottom of Figure 2.

Figure 4 is a perspective view of a cover plate used to seal the opening in the top of the container.

Figure 5 is an enlarged vertical sectional view taken along the line 5—5 of Figure 1.

Figure 6 is a sectional view on the line 6—6 of Figure 5.

Figure 7 is an enlarged sectional view of a controlling valve and is taken on the line 7—7 of Figure 5.

Figure 8 is a sectional view of the controlling valve on the line 8—8 of Figure 7 showing the valve in one operating position.

Figure 9 is a similar sectional view of the valve, except in the opposite operating position.

Figure 10 is a perspective view of a flange joint forming a part of the suction mechanism; and

Figure 11 is a plan view of a controlling valve disc.

Referring to the drawings, 1 designates a grease container having a hole 2 at the upper end thereof covered in the present instance by a plate 3. Extending into the container 1 through a hole 4 in the plate 3 is a tube 5 (Figures 2 and 4). The tube 5 terminates at its lower end in a bell shaped member 6, (Figures 2 and 3) which is covered at its lower end by a screen 7. The screen 7 is fastened at its outer periphery to the bell member 6 in any suitable manner, or as in the present instance by a screw 8 inserted through the screen into a bridge 6a which forms a part of the member 6.

At the end of the tube 5 opposite that end carrying the member 6 is a flange 9 connecting with and bolted to another flange 10 which is fastened to the lower end of a tube 11 projecting from the bottom of a pump piston 12. The purpose of the tube 5 and the associated parts just mentioned will be explained hereinafter.

Slidably mounted for reciprocatory movement over the top of the piston 12 is a cylinder 13. The cavity formed between the top of the piston 12 and the internal upper surface of the cylinder 13, it is evident, will be increased in volume when the cylinder ascends, and will be decreased when it descends. It is evident that with the tube 5 immersed in the grease 1a of the container 1, upon an upward travel of the cylinder 13, grease will be sucked from the container 1 into the tubes 5 and 11 and from the tube 11 into a passage 14 of the piston 12. Internal of the piston 12 is another passageway 15 uniting at its lower end with a delivery line 16 (Figure 5). At the upper end

of the piston 12 is a valve 17 which in the present instance is shown as a flat disc prevented from falling out of the valve retaining cavity by a bent wire 19. Located in the delivery line 16 is a check valve 20 which permits grease to flow from the passageway 15 into the line 16 but which prevents a return flow from the line into the passageway. It is also evident that the valve disc 17 prevents grease internal of the cylinder 13 from returning 10 into the passage 14, as is also more fully described hereinafter.

A second cylinder 21 is mounted over the cylinder 13 and the cylinder 13 is slidably arranged for reciprocating therein. The top end of the cylinder 21 is closed. The other end thereof is open and is fastened by screws 22 to the upper portion of a spacer 23. The spacer 23 serves to hold the cylinder 21 in operating relation to the cylinder 13. The lower end of the spacer is fastened by screws 24 to an outstanding base portion 18 of the piston 12. (Figure 5.)

The cylinder 13 near its upper end is enlarged to form a flange 25 which serves as a support for cup leathers 26. Ring members 27 are arranged, 15 one in each cup leather 26 and clamped against the leathers by screws 28 which project through the lower ring 27, the flange 25 and both leathers 26, and are screwed into tapped holes in the upper ring 27.

At the upper end of the spacer 23 are screws 30 holding a ring 30 which clamps a cup leather 31 into operative contact with the lower, outer periphery of the cylinder 13. At the lower end of the cylinder 13 is a ring 32, a spacer 33 and 25 cup leathers 34, all secured to the lower end of the cylinder 13 by screws 35.

A pipe 36 carries, in the present instance, compressed air into a valve chamber 37 through a valve cover 38. A valve disc 39 is mounted for 40 rotating movement on a valve seat 40 and is guided by engagement of its periphery with a bored out portion 39a of the valve body 41 against other than rotary movement on the seat 40 (Figure 7). The valve seat 40 has a port 43 leading to the upper end of the cylinder 21 through a pipe 44. A port 42 leads to the lower end of this cylinder 21 through a pipe 36a. Both the pipes 36a and 44 are fitted with unions 45 to facilitate ready assembly. A third port 46 leads 45 from the valve seat 40 to external of the valve body 41. Coacting with the valve 39 at its end opposite the seat 40 is a valve stem 47. Its end is flattened to enter into a rectangular slot 48 in the valve 39 (Figures 7 and 11). Internal of 50 the stem 47 and at this same end is a hole carrying a coiled contractile spring 49. The center portion of the stem 47 is enlarged into a bevel seat coacting with, and arranged for rotary movement in, a beveled seat portion of a Babbitt sealing ring 50 carried in the cover 38. The end of 55 the valve stem 47 opposite the valve disc end carries, for fixed movement therewith, one end of a lever 51. It is evident that when air pressure enters through the pipe 36 into the valve chamber 37, it presses the valve disc tight against the seat 40 and at the same time the bevel seat of the valve stem 47 is pressed into sealing contact on the Babbitt ring 50. The valve disc 40 contains a port 52, which, in Figure 8, is shown off 60 contact from the port 42 and a port 53 is shown in Figure 9 as off contact from its associated port 43. A slot 54 on the under side of the disc 39 unites the port 42 with the exhaust port 46 when the inlet port 53 is contacting with the port 43 as 70 shown in Figure 8. The slot 54 unites the port 75

43 with the exhaust port 46 when the inlet port 52 is contacting with the port 42, as in Figure 9. It is now evident that with the valve disc rotated to the position shown in Figure 8, compressed air will pass from the pipe 36 into the valve chamber 37, through the port 52 into the port 43 and the pipe 44, then to internal of the cylinder 21, forcing the cylinder 13 downward and forcing grease disposed internal of the cylinder 13 into the passage 15 and through the pipe 16, the check valve 20, and a delivery hose 20a to a shut off nozzle 21a. It is also evident that upon reverse operation of the valve disc 39 to the position shown in Figure 9, the air trapped internal of the cylinder 21 will be released to atmosphere 80 through the slot 54 and the port 46 by reason of the port 46 being united by the slot 54 with the port 43 and the pipe 44. Also that with the valve disc in the position shown in Figure 9, compressed air will flow from the pipe 36 into the pipe 36a and the lower end of the cylinder 21 thereby elevating the cylinder 13 to the position shown in Figure 5. Upon this upward movement, it is now evident that grease will flow to internal 90 of the cylinder 13 from the passage 14, being forced thereinto by atmospheric pressure on the grease 1a in the container 1.

In order to control this pumping movement of the cylinder 13 automatically, I have provided a rod 55, slidably passing through the ring 32, the cups 34 and the spacer 33, a head 56 being screwed onto the upper end thereof. On the lower end of the rod 55 is screwed an enlarged portion 57 into which is fastened pins 58 and 59. The portion 57 is guided for reciprocatory movement in a hole 60 drilled through the web of the piston 12 as shown in Figure 5. Pivoted on a lug 61 extending from the base of the piston 12 is a lever 62, the lever being rockable about its pivot screw 63. To one end of the lever 62 is pivoted for rocking movement, one end of a link 64. The opposite end of this link is slotted, a pin 65 extending out from the free end of the lever 51 for travel in the slot therein. Between a pin 66 extending out from the link 64, and 100 a pin 67 extending from the lever 62, is a coil extension spring 68, which serves to hold the parts 62-64 and 51 in the relation one to the other as is shown in the full line position (Figure 5) or the dotted center line position, 62a-64a 105 and 51a. It is evident that this full line position of the linkage 62-64 and 51 brings the valve disc 39 into the position shown in Figure 8 and that the dotted center position 62a-64a and 51a 110 brings this valve into the position shown in Figure 9. Also it is evident that these two positions of the linkage are obtained by up and down travel of the cylinder 13 alternately moving the upper leather 34 into contact with the end 56 of the rod 55 and then the ring 32 into contact 115 with the shoulder formed by the upper end of the enlargement 57, for thus bringing the pin 59 into contact with the lever 62 and then the pin 58 into contact therewith. In Figure 5, the pin 59 has already contacted with the lever 62 120 and forced it past the center line formed by drawing a line between the pivots of the levers 51 and 62 and the spring 68 has snapped the lever 62 away from contact with the pin 59 and into the full line position shown. As this is a 125 conventional form of toggle movement, it is thought that no further description or disclosure is needed. The valve body 41 is fastened into the base portion of the piston 12 by screws 70. 130

Any suitable method may be used for mount- 135

ing the pump assembly upon a wall 70a as for instance by providing a bracket 71 as shown in Figures 1 and 2.

The cover plate 3 has four spring-like straps 72 riveted to it so that they have rubbing contact with the tube 5. It is evident that the plate will remain at any point on the tube 5 to which it may be moved by reason of the spring tension effect of the straps 72.

10 The operation of the device is as follows:

The cover plate 3 is removed from the original container 1 of grease or other lubricant that will flow, and which it is desired to deliver through piping to a source of use. Into this opened top 15 is inserted the tube 5 with its associated end 6.

At the top end of the tube 5 is screwed the flange 9. This flange has slots 75 and 76, which line up with the bolt holes in the flange 10 carried by the pipe 11. Two bolts 77 and nuts 78 are now tightened, holding the two flanges together and permitting flow of grease up through the tube 5 into the tube 11 and the piston 12 when the cylinder 13 is reciprocated in pumping operations. A gasket 78a can be inserted between the abutting surfaces of the flanges 9 and 10 if this is found necessary to stop leakage. Compressed air is now turned into the pipe 36 and the pumping cycles will start and continue until the pipe 16 has been filled with grease at a 30 pressure that will balance pressure due to the air on top of the cylinder 13. It will be seen that the area of the head of the cylinder 13 is considerably larger than the area of the head of the piston 12. It is evident that the delivery 35 pressure of the grease in the passage 15 will be as many times greater than the entering air pressure in the pipe 36, as the head of the cylinder 13 is greater in area than the head of the piston. This is of advantage as the air pressure seldom 40 runs over 150 lbs. per sq. inch and grease can easily be carried to the pipe 16 at 400 to 600 lbs. per sq. inch, or in fact any pressure that may be found desirable, and which may come within the ratio of cylinder to piston head area.

45 An eyebolt 79 is shown to enable lifting the mechanism easily during its installation or removal from the wall bracket 71.

I wish it understood that the particular form of mechanism illustrated as an embodiment of my invention and the different parts thereof illustrated and described, are merely a typical method of carrying my invention into effect, and that the specific construction described herein is merely by way of illustration and is not to be construed 55 as limiting or narrowing my claims, as obviously, changes in constructions and design can be made without departing from my invention and such

changes are contemplated by me, and would not involve any departure from my invention.

Having thus described my invention what I claim as new and desire to secure by Letters Patent is:

1. For use with a container for grease or the like, a stationary tubular piston having an intake end extending into said container, a tubular plunger over said piston, a stationary cylinder over said tubular plunger and enclosing the end thereof opposite said intake end, means for reciprocating said tubular plunger relative to said tubular piston and said cylinder, a passageway through said piston from the inner end thereof to a point beyond one limit of travel of said plunger through which grease may be expelled from between said piston and said tubular plunger.

2. For use with a container for grease or the like, a stationary tubular piston having an intake end extending into said container, a tubular plunger over said piston, a stationary cylinder over said tubular plunger, said tubular plunger having a closed end located in all positions of its travel within said stationary cylinder, means for introducing fluid pressure into said cylinder for reciprocating said tubular plunger relative to said tubular piston and said cylinder and means for conducting grease from between said piston and said tubular plunger to a point external of said container.

3. For use with a container for grease or the like, a stationary tubular piston having a lower end extending into said container, a tubular plunger over said piston, a stationary cylinder over said plunger having its lower end sealed around said plunger, said tubular plunger having a closed upper end located within said stationary cylinder and enlarged to form a fluid pressure piston and means for alternately introducing fluid pressure above and below said fluid pressure piston.

4. For use with a container for grease or the like, a stationary tubular piston having a lower end extending into said container, a tubular plunger over said piston, a stationary cylinder over said plunger having its lower end sealed around said plunger, said tubular plunger having a closed upper end located within said stationary cylinder and enlarged to form a fluid pressure piston, a passageway through said tubular piston from the upper end thereof to below the lower limit of travel of the lower end of said tubular plunger, and means for alternately introducing fluid pressure above and below said fluid pressure piston.

GEORGE H. HARTMAN.
